UNITED STATES PATENT OFFICE.

BURTON E. CLARK, OF PITTSBURGH, PENNSYLVANIA.

AUTOMATIC GAS SEPARATOR FOR OIL WELLS.

Application filed October 4, 1921. Serial No. 505,238.

To all whom it may concern:

Be it known that I, BURTON E. CLARK, a citizen of the United States, residing at Pittsburgh, in the county of Allegheny and 5 State of Pennsylvania, have invented new and useful Improvements in Automatic Gas Separators for Oil Wells, of which the following is a specification.

This invention has reference to automatic 10 gas separators for oil wells, and its object is to separate the gas from salt water accumulating in the oil wells after reaching the surface of the ground, so that the dry gas may be directed into gas mains for use, and 15 the salt water may be saved for the recovery of the salt.

In accordance with the invention, the 20 wells, which may reach a depth of two thousand feet or more, and are appropriately cased as is the custom in such wells, will 25 ordinarily, in the gas-producing sands of West Virginia, Pennsylvania, Ohio and Indiana, pierce a formation, known as wet sand. This sand or sandstone, as it is known, contains salt water, oil and gas. 30 Under ordinary conditions heretofore prevailing, the valves, pumps and other machinery, designed to save the gas in a dry and salable condition, become useless in a very short time, by reason of the salt water forming a deposit of salt and rust around the working parts.

To avoid these difficulties is the object of 35 the invention and it comprises a simple device without movable parts, which, in use, has proven to be efficient and adaptable to wells of any size.

After drilling a well into the wet sand, as it is called, the well will fill up to a depth 40 of about 1800 feet with salt water and remain there with the gas held back until a head or rock pressure has formed sufficient to lift this 1800 feet of water in the casing, when it will usually flow for about two 45 or three minutes until the pressure has become exhausted, when it will settle back as before until another head has formed. After each flow, the gas gets gradually weaker until within a few days it will not raise the 50 water and the well becomes drowned out.

It requires one pound of gas pressure to raise water two feet in a one inch pipe, wherefore, to raise the water 1800 feet requires 900 pounds.

55 To obviate this and save the well, the device of this invention has been evolved and

has been used for eighteen months, and has put about 400,000 feet of gas in the main line daily, and furthermore, has brought up and disposed of over 175 barrels of salt water 60 daily, which water, by analysis, shows one-eighth of its bulk to be solid salt. Moreover, the flow has never stopped and has required no expense.

The invention will be best understood 65 from a consideration of the following detailed description, taken in connection with the accompanying drawings, forming part of this specification, with the understanding, however, that the invention is not confined 70 to any strict conformity with the showing of the drawing, but may be changed and modified so long as such changes and modifications mark no material departure from the salient features of the invention, as ex- 75 pressed in the appended claims.

In the drawing:

Figure 1 is a longitudinal section, more or less schematically displayed, of a gas producing well with the invention applied; 80

Figure 2 is a section on the line 2—2 of Fig. 1.

Referring to the drawings, there is shown a well casing 1, extending from the surface of the ground, to a depth defining the upper 85 surface of a layer or stratum 2, of sandstone infiltrated with salt water, oil and gas, ultimately finding its way into a bore 3, in the sand 2, in which bore the liquid and gaseous elements accumulate. 90

At the bottom of the casing 1, there is lodged a packer member 4, constituting the top of the chamber 3. Extending above the casing 1 and down through such casing, into the bore 3, is a tube 5, which may be of 95 considerably smaller diameter than the casing. At the lower end of the tube 5, there is secured an atomizer cylinder 6, of larger diameter than the tube 5, and of smaller diameter than the bore 3, said cylinder being 100 closed at the bottom and having its only outlet at the top through the tube 5.

In actual practice the cylinder 6 may be considered as four inches in diameter and six feet long with the bottom closed and in which a solid core 7 is installed, rising from the closed bottom of the cylinder toward the top thereof for about three feet. On four sides of the cylinder there is produced upright series of six small holes 6^a, 110 extending from the bottom of the cylinder upwardly, or 24 in all. More holes, if made

smaller, may be used or a lesser number of holes, if larger. Without confining the number of holes to 24, such number is preferred.

At the upper end of the cylinder 6 where it is entered by the tube 5 there is produced a single hole 8 at about six inches below where the cylinder is connected to the tubing 5. This hole equals in size two of the holes 6^a in the lower part of the cylinder. The cylinder 6 operates as an atomizing cylinder, and is connected to the bottom of the tubing 5 within bore 3, in such way that it will be practically at the bottom of the well, and inside the zone of high pressure.

The tubing 5 is continued to and extended up from the surface or top of the casing 1, to any desired height, where, by a right angle bend or elbow 9, it is connected to a tank 10, at a point about three-quarters of the distance above the bottom of the tank. This tank 10 is closed at the top and bottom, except for a two inch tubing 11, leading to a point where the gas is to be forced into the main line.

There is installed a valve 12 in the pipe 5 adjacent to the tank 10, and another valve 13 in the tubing 11. Another pipe 14 is connected to the tank 10, at a point near the bottom thereof, and this pipe 14 terminates at the upper end in a downwardly bent return bend 15. The pipe 14 is conveniently made of one inch size and rises to a height about two feet less than the tubing 5 where the latter enters the tank 10. The valve 13 or gate 12 may be located as shown in the drawing or at any convenient point above the surface of the ground, or in the well, when desired.

When the valve 12 is closed a gas head or rock pressure is gradually formed in the bore 3 under the packer 4. On opening the valve 12, a pressure of water, which practically fills the pressure chamber 3 at this stage, allows gas to gradually fill under the packer 4 and force the water down through the holes or perforations 6^a in the cylinder 6 until it reaches a point below the dry gas entrance 8, whereupon the dry gas is forced in at the top of the cylinder 6 which at once relieves half of the gas pressure in the cylinder. The pressure drives the water down and up through the lower holes 6^a after being broken into a spray by coming in contact with the center obstruction 7, under pressure. This spray coming in contact with gas under high pressure entering through the opening 8, is further broken and thoroughly atomized, and is carried up through the tube 5 with very little resistance and is deposited in the tank 10, where the pressure, being released, the water gravitates to the bottom of the tank and the gas accumulates at the top thereof. It now becomes necessary to form an artificial or back pressure in order that the gas can be forced

into the gas main for sale, against a varying line pressure. This is furnished by the action of the upright pipe 14, making a seal at the bottom and extending up two feet for each pound of back pressure required. The varying gas or line pressure in the main 11 will vary the height of water in the separating tank 10. Should the pressure be heavy it would drive the water down in the tank proportionately. Should the pressure be light the water will rise until it reaches a level with the overthrow 15, where the water flows off by gravity.

The advantage of the present invention is that, the gas will find its way into the main without any possibility of water reaching the main 11, but simply passing off by the escape 14-15.

The action of the invention is wholly automatic, requiring absolutely no attention after the installation of the system as a whole. The invention will handle satisfactorily wells with more than the ordinary amount of water and less than the ordinary amount of gas, and the invention has the capacity of gradually exhausting the water and thus increasing the flow of gas.

The main feature of the invention comprises a powerful atomizer system contained in the cylinder 6 as a whole, and the special feature of the cylinder being the entrance 8 for dry gas and which entrance has and performs many functions including the complete atomizing of the already broken water. This prevents the well from being flooded by doubling the gas pressure the moment the water rises sufficiently to cover the inlet 8 and the water is forced to recede to the capacity of the lower holes of the cylinder 6, when it instantly and automatically again assumes the function of atomizing the broken spray, carrying it out at a greater speed until the well again becomes normal, whereby the action is that of a governor over the whole system.

What is claimed is:—

1. In an oil and gas well, provided with a closed cavity or bore in the lower gas bearing strata, an atomizer structure for location in the cavity, a separating tank for gas and water located at the upper end of the well, a pipe connecting the atomizer structure with a high point of the separating tank with the latter provided with a liquid overflow determining the accumulating level of liquid therein, and connections from the separating tank to a gas main, the atomizing structure having water and gas inlets at a low point and a single gas inlet at a high point.

2. In an oil and gas well, provided with a closed cavity or bore in the lower gas bearing strata, an atomizer structure for location in the cavity, a separating tank for gas and water located at the upper end of the

well, a pipe connecting the atomizer structure with a high point of the separating tank with the latter provided with a liquid overflow determining the accumulating level of 5 liquid therein, and connections from the separating tank to a gas main, the atomizing structure having water and gas inlets at a low point and a single gas inlet at a high point, the single gas inlet having substantially twice the area of any one of the gas and water inlets.

3. In an oil and gas well provided with a closed cavity or bore in the lower or gas bearing zone, an atomizer structure located 15 in the cavity, a separating tank for gas and water located at the upper end of the well, and a pipe connecting the atomizer structure with the high point of the separating tank, the atomizer structure being provided with 20 a centralized core and peripheral perforations rising to substantially the same height and terminating at about intermediate of the height of the atomizer structure, a single perforation through the cylinder of about 25 twice the area of one of the first-named per-

forations and located closely adjacent to the top of the cylinder, and a liquid and gas pipe rising from the top of the cylinder and extending to the top of the well.

4. In an oil and gas well, provided with a closed cavity or bore in the lower or gas-bearing strata, an atomizer structure for location in the cavity and comprising a cylinder having perforations in the lower end to about half the height of the cylinder, a core 30 in the cylinder rising to about the same height, a pipe connected to and rising from the top of the cylinder, a tank at the top of the well opening into the tank near the upper end thereof, and provided with a cut-off 35 valve in accessible position, valved connections from the top of the tank to a service main, and an equalizing pipe rising from the bottom portion of the tank to a determined height, less than the connection of the valve 40 pipe with the tank.

In testimony, that I claim the foregoing as my own, I have hereto affixed my signature.

BURTON E. CLARK.
